UNITED STATES PATENT OFFICE.

JOHN M. KELLER, OF NEOGA, ILLINOIS.

PORTABLE FENCE.

SPECIFICATION forming part of Letters Patent No. 236,892, dated January 25, 1881.

Application filed December 6, 1880. (No model.)

To all whom it may concern:

Be it known that I, JOHN M. KELLER, of Neoga, Cumberland county, State of Illinois, have invented certain new and useful Improvements in Portable Fences, of which the following is a specification.

My invention is a portable fence, constructed, as fully described hereinafter, to secure lightness, strength, ease in erecting and rigidity, and immobility when erected.

In the drawings, Figure 1 is a side view of a section of my improved fence. Fig. 2 is a transverse section on the line 1 2, Fig. 1, looking in the direction of the arrow; Fig. 3, a side view of one of the fence-sections, and Fig. 4 a plan.

The fence consists of panels A and their supporting devices, each vertical post B consisting of two bars, each constituting one of the bars *a a'* of a panel, the cross-bars *c* of which are nailed to the vertical bars, as shown. The cross-bars have ends *e* projecting beyond the vertical bars, and when two adjacent panels are placed in line the end bars, *a a'*, thereof will be in contact, and the ends *e* of the cross-bars will hold the post-bars in line.

To prevent the fence from falling laterally I use diagonal stays *d d'*, each having its bearing on the ground at one side and against one of the posts beneath a cross-bar, as shown, the stays on opposite sides of the same post being out of line, so that a cross-strip, D, passed through the post will bear against the stay *d* on one side and against the stay *d'* on the other, thus preventing longitudinal movement of the fence liable to occur when the fence is on an incline.

The division of each post into two bars renders available light inexpensive strips which have not heretofore been considered serviceable for such purposes, and further permits the

cutting, with an ax, of corresponding notches, which constitute the opening *x*, for the reception of the cross-piece D, thus avoiding the necessity of mortising with a chisel.

45

Greater permanency is secured, especially when the ground is soft and spongy, by means of base-strips I, notched to receive the ends of the posts, as shown, and the whole structure is bound together and stiffened by a wire, *t*, 50 (which may have barbs,) running through eyes at the top of the posts, and securely attached to the opposite end posts of the fence or section.

A ready mode of securing the wire is by 55 staples *u*, and these are driven each with its prongs into the ends of the opposite bars of the post, so as to aid in holding the two together.

The fence thus constructed is light, strong, durable, easily erected, stable and rigid when 60 in place, and may be cheaply constructed of lighter materials than that usually employed.

I claim—

1. A portable fence the posts of which are composed each of two bars, of adjacent panels, each panel having cross-bars with projecting ends *e*, and the adjacent bars being notched to form an opening to receive a cross-strip, D, as set forth.

2. The combination, in a portable panel-fence, of divided posts B, of staples *u*, driven with one prong in each bar of the post, and a wire, *t*, extending through the staples and secured to the end posts of the fence, as set forth.

75

In testimony whereof I have signed my name to this specification in the presence of two subscribing witnesses.

JOHN M. KELLER.
